UNITED STATES PATENT OFFICE.

MATHEW J. WEBER, OF COLUMBUS, OHIO, ASSIGNOR TO THE OHIO PUMP & BRASS CO., OF COLUMBUS, OHIO.

ELECTRICAL-SWITCH MECHANISM.

1,203,287.

Specification of Letters Patent. Patented Oct. 31, 1916.

Application filed May 15, 1915. Serial No. 28,432.

To all whom it may concern:

Be it known that I, MATHEW J. WEBER, a citizen of the United States, and a resident of Columbus, in the county of Franklin and State of Ohio, have invented certain new and useful Improvements in Electrical-Switch Mechanism; and I do hereby declare the following to be a full, clear, and exact description of the invention, such as will enable others skilled in the art to which it app pertains to make and use the same.

This invention relates to improvements in electrical switch mechanism and more particularly to such as may be employed for automatically controlling the operation of the actuating motor of a pump employed for storing water in a tank or reservoir,—one object of my present invention being to so construct the mechanism that it shall be positive, sure and accurate in its operation.

A further object is to provide simple and efficient means for insuring the retention against accidental movement of the switch arm or lever in the position to which it may be moved, and more particularly when it is in engagement with the stationary contact so that the circuit will not be interrupted until the switch is positively snapped open.

With these and other objects in view, the invention consists in certain novel features of construction and combinations of parts as hereinafter set forth and pointed out in the claims.

In the accompanying drawings; Figure 1 is a view of a switch mechanism embodying my improvements showing the positions of the parts when the circuit of the switch is closed, and Fig. 2 is a view showing the switch closed.

1 represents a suitable frame, one wall of which may be cut away to receive a block or plate 2 of insulating material. The frame 1 also supports a casing 3 in which a piston in the form of a diaphragm 4 is secured. A nipple 5 is secured to and communicates with the casing 3 and adapted for the reception of a pipe (not shown) to be connected with a tank or reservoir into which water is forced by means of a suitable pump, the latter being operated by means of electric motor (not shown). The purpose of my improved switch mechanism is to automatically control the operation of this pump in accordance with the varying pressure of the water in said reservoir.

The casing 3 is provided with an interiorly

threaded cylindrical extension 6 for the reception of a threaded sleeve 7, and a spring 8 is located within the part 6 so as to be disposed between the inner end of the sleeve 7 and the diaphragm 4. The head 9 of the sleeve 7 is perforated for the passage of a rod 10, the inner end of which is secured to the diaphragm 4.

A post 11 projects from the frame 1 and on this post, a lever 12 is mounted, said lever being made with a short arm 13 and a longer arm 14. An L-shaped arm 15 is secured to the free end of the rod 10 and the shorter member of this arm is recessed to form a hook 16 which loosely engages the short arm 13, of lever 12.

A balanced lever 17 is loosely mounted on a post 18 fixed to the frame 1 and is made at one end with a head or enlargement 19 having an elongated slot 20. The head 19 is made with an arm 21 to which a block 22 of insulating material is secured, for the purpose of pressing one end of a spring contact member 23 into engagement with a fixed contact 24 supported by the insulating plate 2 and connected with a binding post 25. The spring contact arm is secured to and electrically connected with a binding post 26 on the plate 2 and is so formed that its free end will normally tend to spring away from the fixed contact 24 when the block 22 on lever 17 recedes, and thus open the circuit in which the binding posts and switch contact devices are included, said circuit also including an electric motor (and a suitable source of electrical supply) for operating a pump to force water into a tank.

An arm 27 is loosely mounted on the post 18 and from its free end a pin 28 projects and enters the slot 20 in the head of the balanced lever 17. The free end of the arm 27 is connected, by means of a spring 29 with the free end of arm 14 of lever 12, so that when the latter is oscillated and its arm 14 moves beyond a line passing through said arm 14 and the pivotal support of arm 27, the latter will be operated to actuate the balanced lever 17 and open or close the switch.

For the purpose of retaining the balanced lever 17 in position while the pin 28 is moving relatively to the lever,—particularly when the spring switch member 23 is being pressed against the fixed contact 24, a brake lever 30 is employed. This brake arm is pivoted to the frame 1 and is pressed into engagement with a lug or shoulder 31 on

the head of lever 17 by the action of a coiled spring 32. One end of this spring may be secured to an arm of the brake lever and its other end passed through a tubular screw 33 passing a wall of the frame 1, said spring having a head 34 at its free end. It is apparent that by adjusting the screw 33, the tension of the spring and consequently the pressure of the brake lever against the lug or shoulder 31 may be regulated.

During the operation of the pump, by means of the electric motor as previously explained, the spring switch member 23 will be in electrical engagement with the fixed contact 24 to keep the circuit closed. During the filling of the tank by the operation of the pump, the pressure thereon will gradually increase and this pressure will cause movement of the diaphragm 4 to be transmitted through rod 10 and 15 to the L-shaped lever 12. The movement thus transmitted to the lever 12 will, through the connection 29 of its arm 14 with the arm 27, cause the latter to move and carry the pin 28 gradually through the slot 20 in the head 19 of balanced lever 17. As the pin 28 moves through the slot 20 and until the arms 14 and 27 become disposed in alinement with each other with the pin 28 located centrally between the ends of the slot 20, pressure of the insulating block 22 against the free end of the spring member 23 would be so relieved that the latter would tend to vibrate and thus disturb the continuity of the motor circuit. To prevent this and insure the maintenance of a perfect electrical contact between the switch members 23 and 24 until the predetermined pressure in the tank has been reached, is the principal office of the brake device 30. When the predetermined pressure in the tank has been reached, the arm 14 of lever 12 will be moved beyond alinement with the arm 27 and its pivotal support, and hence said arm 27 will be moved quickly through the medium of the action of spring 29 and the pin 28, engaging the end wall of the slot, will cause the balanced lever to be moved quickly and the switch snapped open. The opening of the switch will result in the stopping of the electric motor and of the pump. During the recession of pressure in the tank, the movements of the parts will be the reverse to those above described,—the balanced lever carrying the insulating block 22 being retained in withdrawn position by the action of the brake device 30 until the arm 14 of lever 12 passes alinement with the arm 27, when the switch will be snapped to closed position and the motor will then be again started to operate the pump for replenishing the water in the tank.

Having fully described my invention

what I claim as new and desire to secure by Letters-Patent, is:—

1. In a switch device, the combination with a contact member and a spring switch member coöperable therewith and tending normally to spring away from said contact member, of a pivoted lever coöperable with the spring switch member, to press the latter against the contact member, a pivoted arm having a lost-motion connection with said lever, means for operating said arm to operate the lever, and a brake device coöperable with said lever to hold it in position to which it may be moved.

2. In a switch device, the combination with a switch member and a contact device coöperable therewith, of a pivotally supported balanced lever coöperable with said switch member, a pivoted arm, a lost-motion connection between said arm and balanced lever and operative to cause the lever to move the switch member into engagement with the contact device, a spring pressed brake device engaging said balanced lever to hold the same in position when the switch is closed and during the lost-motion movement of the pivoted arm relatively to the lever, and means for operating said pivoted arm to operate the balanced lever and effect the opening and closing of the switch.

3. In a switch device, the combination with a switch member and a contact coöperable therewith, of a pivotally supported balanced lever coöperable with said switch member, a pivoted arm having a lost-motion connection with said balanced lever, a pivoted lever, a spring connecting said pivoted lever with the pivoted arm, means for operating said pivoted lever, a brake lever, a spring pressing said brake lever against the first-mentioned lever, and means for adjusting the tension of said spring.

4. In a switch device, the combination with a spring switch member and a contact device coöperable therewith, of a pivoted lever to coöperate with said spring contact member and having an elongated slot, a pivoted arm provided with a pin entering said slot, an L-shaped lever, a spring connecting one arm of said L-shaped lever with said pivoted arm, a fluid pressure device, and an arm connected with said fluid pressure device and with the other arm of said L-shaped lever.

In testimony whereof, I have signed this specification in the presence of two subscribing witnesses.

MATHEW J. WEBER.
